UNITED STATES PATENT OFFICE.

BENJAMIN E. D. STAFFORD, OF PITTSBURGH, PENNSYLVANIA.

COLLAPSIBLE TUBE AND CONTAINER FOR THE SAME.

1,382,135.

Specification of Letters Patent. Patented June 21, 1921.

Application filed August 1, 1919, Serial No. 314,737. Renewed May 3, 1921. Serial No. 466,537.

To all whom it may concern:

Be it known that I, BENJAMIN E. D. STAFFORD, a citizen of the United States, and a resident of Pittsburgh, in the county of Allegheny and State of Pennsylvania, have invented certain new and useful Improvements in Collapsible Tubes and Containers for the Same; and I do hereby declare the following to be a full, clear, and exact description of the invention, such as will enable others skilled in the art to which it appertains to make and use the same.

My invention relates to an improvement in a collapsible tube and a container for the same.

Many toilet and medical preparations are put up and sold in tubes which are made of a flexible sheet material and are compressed to eject the contents from a nozzle provided thereon, and containers have been provided for holding the tube, the contents of the tubes being ejected by turning a slotted key applied to the end of the compressible tube. In all instances however, of which

I am aware, the containers have been designed to receive the ordinary flexible tube of commerce and in no instance has the collapsible tube formed a part of the container.

My invention therefore consists in a collapsible tube, the head of which constitutes the head of a container adapted to cover and protect the collapsible tube. It further consists in a collapsible tube the head of which constitutes the head of a container adapted to cover and protect the collapsible tube, the container having one or more finger slots through which a finger or fingers may be inserted for ejecting the contents of the tube.

In the accompanying drawings Figure 1 is a view in longitudinal section of my improved collapsible tube before it is filled; Fig. 2 is a similar view of the container; Fig. 3 is a view of the two parts assembled; Fig. 4 is an enlarged view in section of the nozzle of the tube and its cap; Fig. 5 is a view partly in section and partly in elevation of a modification and Fig. 6 shows the preferred manner of closing and sealing the open or rear end of the collapsible tube.

10 represents the collapsible tube cylindrical in shape and open at its rear end for filling. After the tube has been filled with the paste or other preparation the end is closed and folded and the folded end crimped as shown in Fig. 6, the crimping operating to not only shorten up the flattened end

formed by closing and folding the open end of the cylinder, but also to strengthen the same and prevent the fold from opening when pressure is exerted upon the side of the tube to eject the contents. The front or head end 11 of tube is made considerably thicker than the body of the tube so that it will be stiff and rigid instead of pliable, as is the body of the tube, and is provided with a peripheral rib 12, preferably milled or roughened on its outer face, which rib not only braces and stiffens the head but also enables the head to be readily grasped and held while attaching and detaching the container.

The head 11 is also provided centrally with the outwardly projecting threaded nozzle 13 closed by a screw cap 14, the end of the nozzle being beveled and adapted to bear against a similarly shaped seat within the cap 14, as shown in Fig. 4 for forming a closure that will be air tight and secure against any leakage.

The end of the collapsible tube at its junction with the head is also thickened and provided externally with screw threads 15 for the attachment of the container 16, which latter is preferably cylindrical in form and of a size to receive the tube 10. It is threaded internally at its upper end to engage the threads 15 at the outer end of the tube, and also preferably threaded internally at its lower end for the attachment of the base or end closure 17. This base or end closure may however be formed integral with the container 16 as shown in Fig. 5. The container is provided with one or more finger slots 18, through which a finger or fingers may be inserted to engage the tube for compressing the same to eject its contents.

In the present instance I have shown two curved slots to receive the ends of the fingers of the hand holding the container, but it is apparent that the slots may be straight, or I may use only one.

In the construction shown in Fig. 5 I have shown the base or closure 17 of the container integral with the latter and have also shown the container connected to the head by a bayonet joint 19, the contacting surfaces of the thickened outer end of the tube 10 and the outer end of the container being beveled so that they will make an air tight fit when drawn together by the bayonet joint.

With these constructions the tubes 10 may be filled and sold like the ordinary tubes

now in common use to be used with the container purchased separately or given away with two or more tubes of the paste or other preparation, or they may be applied to the 5 tubes and sold with them.

Again the tube is complete in itself and may be used without the container. The latter however forms an ornamental cover for the tube and protects the latter against accidental 10 rupture due to excessive pressure to which the tube is subjected when grasped by the hand and compressed.

It is evident that many slight changes might be resorted to in the relative arrangement of parts shown and described without departing from the spirit and scope of my invention. Hence I would have it understood that I do not wish to confine myself to the exact construction and arrangement 15 of parts shown and described, but

Having fully described my invention what I claim as new and desire to secure by Letters-Patent, is:—

1. A collapsible tube having an integral 25 head provided with a centrally located discharge nozzle, and also provided at its periphery with means for the removable attachment of a container.

2. A collapsible tube having an integral 30 head at one end, the head being provided with a nozzle closed by a screw cap, and also provided with a threaded periphery for the attachment thereto of a container or cover for the tube.

3. The combination of a collapsible tube 35 terminating at one end in a head having a discharge nozzle, and a container open at one end detachably secured to the periphery of said head and provided with a finger slot

40 whereby the contents of the collapsible tube may be ejected by direct pressure of a finger against the same.

4. The combination of a collapsible tube

terminating at one end in an integral head 45 provided with a centrally located discharge nozzle, and also provided at its periphery with means for the removable attachment of a container, the opposite end of said tube being flattened, folded and crimped for closing the same, and a container having an open 50 end adapted to receive said head and be detachably secured to the periphery of the latter whereby the container forms a housing for the body of the collapsible tube, the said container being provided with a finger slot 55 whereby the contents of the tube may be ejected through the nozzle in the head by direct pressure of a finger against the tube.

5. The combination of a collapsible tube 60 having an integral head provided with a centrally located discharge nozzle and also provided at its periphery with means for the removable attachment of a container and a container open at one end to receive the body of the tube and provided at said open 65 end with means for attachment to the head of the tube, the said container having a finger slot therein whereby the contents of the tube may be ejected through the nozzle in the head by direct pressure of a finger 70 against the tube.

6. The combination of a collapsible tube terminating in a head having a centrally located discharge nozzle, and a container having a finger slot at its side and open at one 75 end to receive the body of the tube, the said open end of the container being closed by the head of the tube to which the container is detachably secured.

In testimony whereof I have signed this 80 specification in the presence of two subscribing witnesses.

BENJAMIN E. D. STAFFORD.
